LADY'S UNDERGARMENT

Mary K. Janin, Port Credit, Ontario, Canada

Application July 16, 1947, Serial No. 761,350

5 Claims.

(Cl. 2—224)

1

This invention relates to improvements in ladies' garments and more particularly to panties to be worn periodically.

One of the objects of the invention is to provide a panty of extremely light weight, the body of which consists of a base or foundation of open mesh fabric, such as textile net. In accordance with the invention, the net is gathered at the top and secured to a narrow band of elastic material so that the garment will snugly embrace the waist of the wearer. The crotch portion of the garment is also gathered at its opposite side edges and such edges are secured to a panel of an impervious lining of thin sheet rubber or the like, such panel having a rear edge portion secured to the buttocks part of the body of the garment by stitching or the like.

One end of the crotch portion is secured to the front of the waist encircling portion of the garment by any suitable means such as a zipper fastening so that the crotch portion may be released from the front of the body to facilitate the attachment or removal of a sanitary napkin. Also in accordance with the invention, the gathered side edges of the crotch portion are stitched to elastic strips which are designed to circle the limbs of the user when the garment is worn.

The primary object of the invention is to provide a feather weight garment of simple, inexpensive construction, and one designed particularly for use with a sanitary napkin, the construction being such that when the garment is worn it will snugly embrace the waist and limbs of the wearer and will provide an impervious protection for the napkin.

With the foregoing objects outlined and with other objects in view which will appear as the description proceeds, the invention consists of the novel features hereinafter described in detail, illustrated in the accompanying drawing, and more particularly pointed out in the appended claims:

In the drawing:

Fig. 1 is a front elevation of my improved panty with the crotch flap in open position.

Fig. 2 is a fragmentary vertical sectional view with the flap in closed position.

Referring to the drawing, 3 designates the body of the garment preferably made of light weight textile net and comprising a body encircling portion of endless form. The upper edge of the body encircling portion is gathered, as indicated at 4, and stitched to a narrow band of elastic tape 5 or the like. It is obvious that the body encircling portion may be of one-piece or consist

2

of a front 6 and a back 7, stitched together at the sides thereof.

In keeping with the invention, a length of inelastic tape 8 is stitched to the medial portion 5 of the front 6 at the lower edge thereof, and a crotch flap 9 is integral with and extends downwardly from the back of the garment. An inelastic length of tape 10 is stitched to the end of the flap, and the lengths of tape may be detachably secured together by any suitable means, such as a hookless fastener 11.

The flap is lined with a liner 12 of any suitable light, impervious sheet material and the opposite side edges of the liner and flap are gathered, and 15 stitched to strips 13 of elastic tape which extend from the ends of the tape 10 to the ends of the tape 8 so that the elastic strips 13 will snugly embrace the limbs of the wearer.

One end of the liner is stitched to the tape 20 10 and its other end is preferably of arc shape, as indicated at 14, and the arcuate edge is stitched to the back of the body of the garment.

To facilitate the attachment of a sanitary napkin, a loop 15 is connected to the medial portion 25 of the tape 10, and a narrow strip of impervious material 16 has its end portions stitched to the liner. The strip 16 between its ends, is loose with reference to the liner so that a sanitary napkin connected to the loop 15 may be threaded 30 through the space between the strip 16 and the liner. As the strip 16 extends crosswise of the crotch flap, it will be understood that it will hold a napkin in spaced relation to the opposite side edges of the crotch flap, a desirable position from 35 a sanitary standpoint.

From the foregoing, it is believed that the construction, use and advantages of my improved garment may be readily understood, and it is apparent that changes may be made in the details 40 disclosed without departing from the spirit of the invention, as expressed in the following claims:

What I claim and desire to secure by Letters Patent is:

45 1. A panty or the like, comprising a front portion and a back portion constituting an endless body encircling structure gathered at its upper edge, an elastic band secured to said gathered edge and adapted to snugly embrace the waist 50 of the wearer, one of said portions having a lower edge provided with a length of inelastic tape positioned between and spaced from the sides of the garment, the other portion being provided with a crotch flap extension having at its end a length 55 of inelastic tape, means detachably connecting

the lengths of inelastic tape to one another, limb encircling elastic tapes secured to the lower edge of one of said portions and to the side edges of the flap and extending from the end portions of the first-mentioned length of inelastic tape to the end portions of the second-mentioned length of inelastic tape, a liner of impervious sheet material lining the flap and secured to the opposite side edges and end of the flap, and means for detachably securing a sanitary napkin to the lined flap.

2. A panty or the like, comprising a front portion and a back portion constituting an endless body encircling structure gathered at its upper edge, an elastic band secured to said gathered edge and adapted to snugly embrace the waist of the wearer, one of said portions having a lower edge provided with a length of inelastic tape positioned between and spaced from the sides of the garment, the other portion being provided with a crotch flap extension having at its end a length of inelastic tape, means detachably connecting the lengths of inelastic tape to one another, limb encircling elastic tapes secured to the lower edge of one of said portions and to the side edges of the flap and extending from the end portions of the first-mentioned length of inelastic tape to the end portions of the second-mentioned length of inelastic tape, a liner of impervious sheet material lining the flap and secured to the opposite side edges and end of the flap, the opposite side edges of the flap and liner being gathered, and means for detachably securing a sanitary napkin to the lined flap.

3. A panty or the like, comprising a front portion and a back portion constituting an endless body encircling structure gathered at its upper edge, an elastic band secured to said gathered edge and adapted to snugly embrace the waist of the wearer, one of said portions having a lower edge provided with a length of inelastic tape positioned between and spaced from the sides of the garment, the other portion being provided with a crotch flap extension having at its end a length of inelastic tape, means detachably connecting the lengths of inelastic tape to one another, limb encircling elastic tapes secured to the lower edge of one of said portions and to the side edges of the flap and extending from the end portions of the first-mentioned length of inelastic tape to the end portions of the second-mentioned length of inelastic tape, a liner of impervious sheet material lining the flap and secured to the opposite side edges and end of the flap, a loop secured to the medial portion of the length of inelastic tape at the end of the crotch flap to facilitate securing a sanitary napkin to the lined flap, and a strip of impervious material extending across the liner and having its end portions secured thereto, the portions of the strip between its end portions being free with reference to the liner to permit the sanitary napkin to occupy a position between an intermediate portion of the strip and the liner.

4. A panty or the like, comprising a front portion and a back portion formed of textile net and constituting an endless body encircling structure

gathered at its upper edge, an elastic band stitched to said gathered edge and adapted to snugly embrace the waist of the wearer, one of said portions having a lower edge provided with a length of inelastic tape positioned between and spaced from the sides of the panty, the other portion being provided with an integral crotch flap extension having at its end a length of inelastic tape, means detachably connecting the lengths of inelastic tape to one another, limb encircling elastic tapes secured to the lower edge of one of said portions and to the side edges of the flap and extending from the end portions of the first-mentioned length of inelastic tape to the end portions of the second-mentioned length of inelastic tape, a liner of impervious sheet material lining the flap and secured to the opposite side edges and end of the flap, and means for detachably securing a sanitary napkin to the lined flap and for holding side edges of the napkin in spaced relation to the side edges of the flap.

5. A panty or the like, comprising a front portion and a back portion each formed of textile net and constituting an endless body encircling structure gathered at its upper edge, an elastic band secured to said gathered edge and adapted to snugly embrace the waist of the wearer, the front portion having a lower edge, a substantially horizontally disposed length of inelastic tape positioned between and spaced from the sides of the panty, said tape being stitched to the lower edge of the front portion, the back portion being provided with an integral crotch flap extension having at its end a length of inelastic tape stitched thereto, means detachably connecting the lengths of inelastic tape to one another, a liner of impervious sheet material lining the flap and secured to the second-mentioned length of inelastic tape, the sides of the liner and flap being gathered, limb encircling elastic tapes secured to the lower edge of said front portion and to the gathered edges of the liner and flap and extending from the end portions of the first-mentioned length of inelastic tape to the end portions of the second-mentioned length of inelastic tape, a loop for attaching a sanitary napkin thereto secured to the medial portion of the end of the flap, a strip of impervious material extending across the liner and having its end portions operatively connected to the side edge portions of the flap, said strip being free with reference to the liner between the end portions of the strip to permit the sanitary napkin to be threaded through the space between the strip and liner.
